UNITED STATES PATENT OFFICE.

WILLIAM CHRISTIAN, OF BRIDGEPORT, CONNECTICUT.

DRUM AND METHOD OF MAKING THE SAME.

Application filed September 29, 1921. Serial No. 504,093.

To all whom it may concern:

Be it known that WILLIAM CHRISTIAN, a citizen of the United States, and resident of Bridgeport, in the county of Fairfield and

5 State of Connecticut, has invented certain new and useful Improvements in Drums and Methods of Making the Same, of which the following is a specification.

This application is a continuation in part 10 of my application Serial No. 381,379, for drums, filed October 17, 1919, allowed February 17, 1920, and now forfeited, in so far as the present case relates to subject-matter contained in the forfeited application.

15 The objects of the invention are to provide a drum of greater durability, of better tone, and at greatly less cost than drums now on the market, to equip said drum with novel and durably constructed drum heads, 20 and to perfect a simple and improved method of manufacture whereby said drum heads can be economically produced.

In practice, I preferably construct the shell of the drum and the rims of paper 25 which may be made of layers of compressed paper pulp so treated as to be impervious to moisture, I desirably form the heads proper of the drum of linen or other fabric which is treated so as to be impervious to atmospheric conditions, and which, when stretched 30 in position upon the shell of the drum will remain taut and retain the tone of the drum, and I prefer to arrange bands within the ends of the shell of the drum so that the 35 heads will have a uniform bearing thereon to insure contact so that the vibrations caused by striking the heads will be uniform.

With the above and other objects in view, the drum, its drum head sections, and the 40 method by which said sections are made will now be fully described and will hereinafter be specifically claimed.

In the accompanying drawing forming a part of this specification,

45 Fig. 1 is a perspective view of a form upon which the novel drum head can be made;

Fig. 2 is a fragmentary sectional view of said form, showing the inner ring of the double rim of the drum head fitted thereon 50 and material of the drum head proper located in position to be secured to said inner ring;

Fig. 3 is a fragmentary sectional view, corresponding with Fig. 2, additionally showing 55 the outer ring of the double rim as when

being slid to its position about the material and inner ring, and suggesting the manner in which unnecessary material may be removed;

Fig. 4 is a fragmentary sectional view, 60 corresponding with Figs. 2 and 3, showing the outer ring placed in position it occupies about the material and the inner ring;

Figs. 5 and 6 are, respectively, perspective views of the outer and inner rings of the 65 double rim;

Fig. 7 is a perspective view of a novel drum head section complete;

Fig. 8 is an enlarged side elevational view, 70 partly in section, of the improved drum complete, showing the manner in which the double rims are applied and fastened down;

Fig. 9 is a still larger fragmentary sectional view of one side of the shell of the drum;

Fig. 10 is a fragmentary sectional view 75 through one side of the drum, corresponding with the showing of Fig. 8; and

Figs. 11 and 12 are fragmentary sectional views of one side of a slightly modified form 80 of drum embodying the features of the invention.

In said drawings, 1 denotes the shell of the drum which is preferably constructed of paper that may be formed of sheets of 85 paper suitably treated and wound upon a mandrel to be of desired thickness or made of compressed paper pulp which is commonly used in the production of various articles, it being understood, of course, that 90 when the shell 1 is formed of compressed paper pulp, suitable molds and forms will be used, according to the size of the drum, and that the outer surfaces of the material will be treated to render them impervious 95 to water and not exposed to disintegration through atmospheric conditions.

Drum heads made in accordance with the principles of the invention each comprise a piece of any suitable material 2, but preferably 100 linen or other fabric treated so as to be impervious to atmospheric conditions and to have endurance and tone, adapted to be stretched over an end of the drum shell to constitute drum heads proper, and double 105 rims adapted to snugly fit upon the drum shell, each consisting of an inner ring 3 and an outer ring 4 between which the marginal edge of the piece of material 2 is securely fastened. I preferably construct the rings 110

3 and 4 of paper, which may also be formed by winding strips of paper on a mandrel, or by compressed paper pulp.

The shell 1 is desirably formed at its ends with recesses 5 in each of which is seated a metallic band 6, preferably circular in cross-section, the surfaces of the rings projecting slightly above the edges of the shell 1 so that the drum head material will not contact 10 with the ends of the shell.

It is essential that each double rim at least partially surround a portion of the shell against the end thereof upon which the corresponding drum head is arranged, in order 15 that the double rims can be suitably fastened down by clamps in any ordinary or preferred manner. It is also essential that a circular portion of each piece of drum head material rest firmly against the full circumference of 20 a band 6 or against the full circumference of the corresponding end of the drum shell. As a consequence, the drum heads must be specially constructed. That is to say, the drum head material 2 of each drum head 25 must include a circular portion adapted to fit upon a band 6 or an end of the shell, and a continuous flange adapted to partially surround a portion of the drum shell adjacent the end thereof upon which the particular 30 drum head is fitted, and the marginal edge of the drum head material must be secured between the rings 3 and 4 in such manner that the circular portion is smoothly stretched over said band or end.

I have, therefore, disclosed in Fig. 1 a form upon which the novel drum head can be made, and have suggested in Figs. 2, 3 and 4 the manner in which the steps of the method productive of the drum head are 40 carried out. The form may consist of a hollow cylinder 7 thickened at its midlength, as denoted at 8, to provide a neck 9 at each side of the thickened portion 8 and of a diameter to snugly receive an inner ring 3, 45 and a flat, horizontal surface 10, somewhat greater in width than the ring 3, desirably extending for the full circumference of the hollow cylinder, but one of the necks 9 and surfaces 10 being utilized at a time, as will 50 be clear from Figs. 2, 3 and 4. In practicing the method, I take a ring 3 and fit it upon the neck 9 so that one of its edges rests upon the surface 10, as in Fig. 2. I then apply to the outer surface 11, or a portion 55 thereof, of the ring 3, a suitable adhesive. I next arrange a piece of drum head material 2 over that end of the neck 9 which is spaced from the thickened portion 8, so that the margin of said piece of material extends 60 outwardly and downwardly, as in Fig. 2. I next take a ring 4, apply glue to all or a part of its inner surface 12, and pass said ring 4 down over the material 2 until it is in about the position of Fig. 3. I next, by 65 use of a knife 13 or its equivalent, trim away

the surplus material 2, as will be evident, and I finally move the ring 4 to the position in which shown in Fig. 4, so that one of its edges is against the surface 10. As will be apparent, the drum head of Fig. 7, having 70 a circular disk portion 14 and a continuous flange 15, is thus produced.

The manner in which the double rims are assembled with the shell will be apparent from Figs. 8 and 10. The end of the double 75 rim which carries the drum head material 2 is fitted upon the shell, the material of the drum head being, in the finished drum, arranged within the double rim and being tightly stretched across the end of the shell, 80 or across the band 6 when the same is utilized.

As shown in Figs. 8 and 10, the double rims may be formed with recesses 17 in which are seated metallic bands 18, similar 85 to the bands 6 which prevent wear upon the double rims when the commonly applied clamps 19 are utilized to hold the several elements of the drum together and to regulate the tone of the drum in usual manner. 90 Obviously the bands 18 can be dispensed with, as suggested in Figs. 11 and 12. In the case of the double rim of Fig. 11, the clamps 19 are fastened directly against the material of the double rim. In Fig. 12 I 95 have disclosed a metallic channel strip 20 which is arranged to overlap the end of the double rim to provide a bearing surface for the clamps.

Instead of utilizing clamps 19, I may 100 treat the outer surfaces of portions of the shell adjacent its ends with glue, and then force the double rims upon the shell to draw the material of the head proper taut. When the glue has set, the drum head sections will, obviously, be rigidly held in position. It will, of course, be appreciated that this construction is intended purely for drums of cheaper manufacture.

What I claim is:

1. The method of making drums which consists in first fastening the marginal portion of drum head material between concentric rings leaving a surplusage of the material within the perimeter of the rings, 115 and subsequently placing the rings upon a drum shell and sliding them down to remove slack from the material and to stretch the same over an end of the shell.

2. The method of making drums which 120 consists in first fastening the marginal portion of drum head material between concentric rings leaving a surplusage of the material within the perimeter of the rings, and subsequently placing the rings in inverted position upon a drum shell and sliding them down to remove slack from the material and to stretch the same over an 125 end of the shell.

3. A drum comprising a shell, a drum 130

head consisting of concentric rings and drum head material having its marginal edge secured between said rings to leave slack or surplus in the material, and means 5 for drawing the concentric rings over the shell to stretch the material and to remove slack or surplus therefrom.

4. In a drum, a shell, and a drum head comprising a piece of drum head material 10 shaped to form a circular disk portion and a continuous flange portion, and a double rim consisting of an inner and an outer

ring secured to the margins of the inner and outer faces, respectively, of the continuous flange portions, said circular portion ar- 15 ranged over an end of said shell, said continuous flange portion lying adjacent the wall of said shell, and said double rim situated upon said shell.

Signed at Bridgeport, in the county of 20 Fairfield, and State of Connecticut, this 28 day of September, A. D. 1921.

WILLIAM CHRISTIAN.
